UNITED STATES PATENT OFFICE.

WILBER E. HUNTER, OF MORGANTOWN, WEST VIRGINIA.

DESIGN FOR AN ARTICLE OF MANUFACTURE.

47,490.

Specification for Design. Patented June 22, 1915.

Application filed March 27, 1915. Serial No. 17,548. Term of patent 7 years.

To all whom it may concern:

Be it known that I, WILBER E. HUNTER, a citizen of the United States, and residing at Morgantown, in the county of Monongalia and State of West Virginia, have invented a new, original, and ornamental Design to be Applied to an Article of Manufacture, of which the following is a specification, reference being had to the accompanying drawing, forming a part thereof.

The figure is a view showing my new design.

My design may be etched, stamped, print-

ed, imprinted, embossed or worked on or in or cut upon any suitable glass, china, paper, cloth or other material, or upon any metal or any other suitable material, and may be produced on or in or attached to any desired article of manufacture.

I claim:

The ornamental design for an article of manufacture as shown and described.

WILBER E. HUNTER.
